ROLL SUPPORTING MEANS

Edwin E. Burroughs, Brooklyn, N. Y., assignor to
St. Regis Paper Company, New York, N. Y., a
corporation of New York

Application October 9, 1948, Serial No. 53,710

4 Claims. (Cl. 242—64)

1

This invention relates to devices for supporting cores upon which lengths of material such as paper are wound, and more particularly to means for controlling the position of certain elements of such devices.

In apparatus suggested in the past for rotatably supporting heavy rolls of material as paper, for example, associated with a bag tube making machine, it has been normal practice to provide a pair of fixed upright frames or main support members upon which rests a shaft, the latter in turn passing through the center of a core upon which the paper is wound. Usually the diameter of such a shaft is less than the diameter of the longitudinal passage through the core. Thus means have had to be provided for firmly securing the roll upon the shaft whereby axial sliding and radial movement of the roll are prevented. A pair of conical members which are axially slidably upon the shaft in the manner of sleeves are commonly employed for this purpose, the pointed extremities thereof being pointed inwardly of the roll and toward one another. Such members are urged firmly into the respective mouths of the core's center passage and when in position preferably partially protrude therefrom. They are locked as by a collar, in this position.

Such shaft, conical members and their locking devices are usually of metal and are unusually heavy, unwieldy and require manual moving.

In the past a serious source of difficulty in the making of, for example, paper bags, has been the necessity to use such large and unwieldy shafts, cones, and their related parts. These have had to be handled a number of times every time it has been necessary to change a paper roll. The shaft usually weighs, for example, about one hundred pounds, each cone weighs, for example, about 15 pounds. The loss of time and the expense of handling these elements have caused appreciable overall loss in such manufacturing operations.

Moreover, the frame members for supporting the control shaft on which the paper roll turns, have been rigidly disposed upon a fixed foundation and have not been able to move axially in synchronism or towards or away from one another. Thus the bearings (frames) which support the control shaft have been at a constant distance from one another as determined by the length of the longest roll to be supported, for example, sixty inches. When a relatively short or narrow roll, for example, twenty-eight inches, is so supported upon the shaft in such fixed

2

frames, the shaft will sag. When the roll of paper is paying out considerable bouncing will occur due to springiness or resilience of the sagging shaft. This bouncing produces serious results in such machines as bag tube making devices. For example, the bag tubes may be wrinkled and thus must be rejected. Also, the bouncing may upset the staggered relationship of a plurality of paper webs as in a multi-wall bag tubing machine.

One of the objects of the present invention is to overcome the above difficulties or to reduce them to insignificance.

The above and further objects and novel features will more fully appear from the detailed description when the latter is read in connection with the accompanying drawings. It is to be expressly understood, however, that the drawings are for purposes of illustration only and are not intended as a definition of the limits of the invention, reference for this latter purpose being had to the appended claims.

In the drawings,

Fig. 1 is a front elevation of one form of the present invention;

Fig. 2 is a side elevation of the apparatus shown in Fig. 1;

Fig. 3 is an enlarged detailed view, partly in section and with parts broken away, of a main control means together with certain related elements embodying the present invention;

Fig. 3a is a plan view partly in section of certain of the control shafts and a brake element employed in the present invention;

Fig. 3b is a detail fragmentary view partly in section and with parts broken away showing certain other shafts and elements, as employed in the invention;

Fig. 4 is a plan view partly in section, with parts broken away and with certain parts omitted for purposes of illustration, showing certain of the shafts for governing the relative disposition of the roll supporting frames;

Fig. 5 is a fragmentary view partly in section of certain gearing and related interconnections as employed in a main control station of the invention; and

Fig. 6 is a sectional view taken substantially on lines 6—6 of Fig. 4.

The form of the invention illustrated in the accompanying drawings, by way of example, comprises a pair of upright frame members adapted for supporting a pair of paper rolls, which members, in order to accommodate rolls of differing sizes and to provide rigid support therefor closely

adjacent same to prevent bouncing, are adjustably mounted for relative axial movement upon a carriage, that is, they can be spread apart or moved toward one another. Since it may be desirable to be able to shift a web of the rolled material sidewise or laterally, for example, in order to adjust its position as in a bag tube forming machine, or in order to adjust one web in a staggered position relative to another web, the two frame members are also mounted for synchronous movement in the same direction, that is, they can be shifted together in the direction of the axis of the roll supported thereby.

Referring to the drawings, frame members 10 and 11 are adapted for movement upon a carriage 12 whereby they can be shifted toward or away from one another or shifted together axially for reasons above mentioned.

The frame members 10 and 11 are in axial alignment and are adapted for movement along said carriage 12 by virtue of frame feet members 13 and 14 which rest upon suitable roller bearings, 15 (Figs. 1, 2, 3b and 6). A set of such roller bearings may be provided upon either side of the feet, as shown in Fig. 6. The roller bearings, if desired, can constitute the cross-links of sprocket chains whereby the individual bearings are held in desired spaced relationship.

Drum control means

In order to facilitate the continuous operation of a machine such as a bag tuber which is employed with the present apparatus, provision is made for the mounting upon said frame simultaneously of two rolls of paper. One of these rolls can be paying out to the bag tuber and the other roll can be placed in position upon the frames in preparation for "running in" the new roll of paper shortly before the first roll becomes exhausted. It has been found desirable to position the new or oncoming roll whereby the web thereof can be fed into a so-called "vortex" between the outgoing web and a suitable roller which guides same in its path outwardly of the apparatus. In the form shown, such a guide roller is situated at the lower portion of the apparatus, thereby making it desirable to locate the oncoming roll above the outgoing roll. In order to accomplish this, a pair of angularly shiftable drums 16 and 17 are mounted in respective of said frames 10 and 11 and arbors for supporting the two rolls are, for example, mounted diametrically opposed upon said drums. A first pair of coaxial arbors mounted upon said frames 10 and 11 is indicated at 18, 19, and a second pair similarly mounted is indicated at 20, 21. The heads or knobs of such arbors, which are adapted for extending into the mouths of the paper roll cores, are indicated respectively at 18a, 19a, 20a and 21a. Said arbors are adapted for easy insertion and withdrawal into such paper roll cores, for example, by threaded association with said drums, as indicated at 22 (Fig. 3). Suitable hand wheels are preferably rigidly associated with each of said arbors in order to shift same axially for insertion or withdrawal. Suitable arbor shoulders as at 20b (Fig. 3) are provided which are movable closely adjacent the core of the roll to prevent undesired shifting.

The two arbors on a given drum are preferably diametrically opposed, and near the periphery thereof, as shown in Fig. 2, whereby one of the two above-mentioned rolls of paper can be shifted to a lowermost position, thereby moving a coaxial pair of arbors, as 20, 21, into the upper-

most position wherein they are easily accessible for the installation of the replacement roll. The arbors are, of course, situated near the peripheries of their respective frame members, to provide ample clearance between rolls.

As shown in Fig. 2, a first roll 23 has been installed upon the upper pair of arbors and the web thereof 23a is led downwardly around the guide roller 24 which directs the paper web out through a slot 12a in the carriage 12 (see Fig. 1) and thence, for example, to a tube forming machine. In order to maintain a proper tension upon the roll 23, it is desirable to lay thereover a belt 25 having a weight 26 at the free extremity thereof. As the roll 23 diminishes in diameter the weight 26, of course, will drop and means are provided for winding the belt 25 upon a suitable shaft as at 27 as by a crank 28 (Fig. 1) having associated therewith a suitable ratchet and pawl mechanism 29 (Fig. 2).

When it is desired to shift the roll 23 to the lower position, for example, when it is about three-quarters exhausted, in order to prepare for the installation of a new roll, the belt 25 is lifted off of the roll, the drums are shifted angularly 180° preferably in a counterclockwise direction and the roll moves to the lowermost position. In this position, a counter-weighted brake, as at 30, is engaged by the roll which brake is pivotally mounted at 31 and provided with a suitable counter-weight 32. The drums 16 and 17 are held in the desired two angular positions by means, for example, of spring loaded detents as at 33 (Fig. 2) which are adapted for sliding in a suitable bore in each frame member and for engaging frame recesses as at 34 and 35 (Fig. 2). The detents may be lifted by suitable handles as at 36.

It is necessary to shift said drums angularly 40 and synchronously in such a manner that the coaxial pairs of arbors 18, 19 and 20, 21 will remain in coaxial relationship. Such means in the form shown are constituted by a mechanical interconnection. The drums have toothed peripheries thereon as at 16a, 17a (Fig. 3) and the drums are made to shift angularly together by means of interconnected gears which turn upon a common shaft. The latter is referred to as a drum control shaft and is indicated at 37 (Figs. 2 and 4).

The drum 16 is operatively connected to said drum control shaft through the intermediary of an idler gear 38 (Fig. 2) which meshes with the toothed periphery 16a and also with a drum control gear 39 mounted upon said drum control shaft 37. The other drum 17 is similarly associated with a second drum control gear 40 (Fig. 4). In view of the fact that the frame members 10 and 11 are shiftable axially in a manner to appear below, means must be provided for shifting the drum control gears 39 and 40 axially with their respective drums. Such means constitute a yoke member provided upon each frame member respectively adapted for engaging circumferential grooves 39a, 40a in said drum control gears. Such a yoke is illustrated as at 16b (Fig. 6) which engages the groove in gear 39. An analogous yoke is provided for the gear 40.

A conventional tongue and groove interconnection (not shown) exists between the drum control shaft 37 and the gears 39, 40 whereby said gears are coaxially shiftable upon the shaft freely under the influence of said yokes and yet torque can be conveyed thereto from the drum control shaft.

A main control station is provided as at 41 (Figs. 1, 3, 6) having localized therein manual means for rotating not only the drum control shaft 37 but for controlling other adjustments in a manner to appear more fully hereinafter. As shown in Fig. 3, a hand crank 42 is secured to a shaft 43, the latter being rotatably mounted in a housing 44 which contains the operative connection between shaft 43 and the drum control shaft 37. This connection comprises, for example, a sprocket chain 45 which is stretched between suitable sprocket wheels secured to said shafts 37 and 43.

Means for spreading or closing frames 10 and 11

As above mentioned, in order to accommodate rolls of differing sizes and to provide rigid support therefor closely adjacent said rolls to prevent bouncing, means are provided for shifting the frame members axially relative to one another which, in the form shown, comprise a frame spreading and closing shaft 46 which is in threaded engagement with threaded members secured to the frame feet 13 and 14 at 47 and 48, respectively (Figs. 3 and 3b). The threads for engaging the feet 13 and 14 are of opposite direction and preferably of equal pitch whereby rotation of the shaft 46 will spread apart or bring closer together the frame members.

Suitable means are provided for rotating the spreading and closing shaft 46, for example, comprising a centrally disposed gear of substantial length upon said shaft 46 as at 49, the latter being rigidly secured to the former. The gear 49 is of a length equal to the distance through which it may be desired to shift said frames axially in the same direction, in order to insure that a gear 50 (Fig. 3a) will mesh therewith throughout this range of movement.

An operative interconnection is provided between the control station 41 and the frame spreading and closing shaft 49, of which said gear 50 is a part, comprising a shaft 51 (Figs. 3 and 4) upon which the latter gear is mounted and which by means of a suitable sprocket chain 52 is connected to a crank shaft 53, the latter having secured thereto a crank 54. Shaft 53 is mounted at the control station 41 upon the housing 44.

Gear 50 and its shaft 51 are restrained from axial movement by suitable means.

Means are provided for indicating the distance between the frame members comprising a graduated drum 55 (Figs. 3 and 5) mounted upon a shaft 56 at the control station. The indicia upon the graduated drum may be viewed from above the control station through a suitable window 57. The shaft 56 is operatively connected to shaft 53 which controls the interframe distance by means of a suitable gear train as at 58.

Means for axially shifting the frame members in the same direction

In order to make the apparatus substantially more compact and in order to provide for a substantial range of adjustment of the frames 10 and 11 when shifted in the same direction, whereby the control station 41 can be located more closely to the frames than otherwise would be possible, a telescoping shaft arrangement is provided for effecting such frame shifting.

An axial thrust is exerted upon the frame spreading and closing shaft 46 by means of a threaded axial shift shaft 59 (Fig. 3) which is restrained from axial movement and which can

convey such a thrust by rotation thereof through the intermediary of a thrust communicating collar 60 which is restrained from angular movement, for example, by means of a suitable yoke 60a which engages the above-mentioned shaft 51. The thrust transmitting collar 60 is provided with a portion 60b having inwardly extending shoulders adapted to engage a circumferential groove in the shaft 46. Such groove, for example, is formed between a shoulder 46a on the shaft 46 and a removable collar 46b. The groove is near one extremity of said shaft as indicated in Fig. 3. A longitudinally extending recess 46c is formed extending into said extremity and having a mouth at such extremity, which recess is adapted for receiving the above-mentioned threaded axial shift shaft 59. Said collar 60 is also provided with a portion 60c having a centrally threaded bore for engaging the shaft 59. Said collar 46b is situated between the collar parts 60b and 60c and can be secured to the shaft 46 by, for example, a suitable set screw.

In view of the fact that the shaft 59 is restrained from axial movement, and collar 60 is restrained from angular movement, rotation of shaft 59 will transmit an axial thrust to the shaft 46 and thence to the frame members 10 and 11. A rotatable collar 59a (Fig. 3) secured to the shaft 59 between a pair of fixed collars 61 prevents said shaft from moving axially.

A suitable hand crank (not shown) is provided at the control station 41 for rotating shaft 59 through the intermediary of a crank shaft 62 (Figs. 2 and 5), and a sprocket chain 63 passing over suitable sprocket wheels upon the shafts 59 and 62.

In operation, a typical sequence of events is as follows:

Assume that it is desired to mount a roll of paper, for example, sixty inches in length, and forty-two inches in diameter. Crank 54 is rotated and the graduated drum 55 is observed until the frame members are spread apart to the precise distance required. Then the heads of the uppermost pair of coaxial arbors are withdrawn to receive the roll. Thereafter the roll of paper is moved into position and the arbors inserted into the core thereof, web 23a (Fig. 2) is led under the guide roll 24 and through the slot 12a to, for example, a bag tube forming machine. By adjusting the hand crank upon the shaft 62, an axial thrust is transmitted to both of the frame members 10 and 11 through the intermediary of the axial shift shaft 59, the collar 60 and the frame spreading and closing shaft 46. Rotation of the shaft 59 will tend to rotate the collar 60, the latter being restrained from angular movement by action of the yoke 60a and the shaft 51. The co-action of the collar portion 60c and the axial shift shaft 59 will transmit through the collar portion 60b the axial thrust to said shaft 46 whereby the axial alignment of the web 23a is adjusted. Once the alignment of the paper web has been thus adjusted, it is possible to spread or close the frame members to accommodate rolls of differing sizes without further web alignment. This is true because of the equal movement of the frame members with respect to a mid point therebetween as caused by the oppositely threaded portions of the shaft 46 which preferably are of equal pitch.

Assume that it is desired to exhaust the sixty inch roll and to change to a twenty-eight inch roll, namely, a roll having a web twenty-eight inches wide. A "running change-over" between

these rolls cannot be made because of their difference in width. Consequently, it will be necessary to permit the sixty inch roll to pay out completely and thereupon to substitute the new roll after bringing the two frames together into the proper spaced relationship. After the sixty inch roll has become exhausted, the core thereof is removed and the frames 10 and 11 are moved to the position for accommodating a twenty-eight inch roll. The heads of the arbors are withdrawn, the new roll is brought into alignment, and the arbors are inserted into the core, thereby providing closely adjacent the roll a firm support which will not permit any bouncing of the paper roll. Thereafter the new paper roll is partly unrolled for several feet or enough to run the web over the guide roll 24, through the slot 12a, and into the bag fabricating machine. Thereafter the belt 25 is hung over the roll in order to maintain proper tension upon the web as it pays out.

Assume now that we wish to renew the twenty-eight inch roll. It is desirable practice to permit about three-quarters of the diameter of the outgoing roll to pay out while the roll is in the uppermost position, as shown in Fig. 2. At this point the handle 36 at the top of each frame is thrust downwardly thereby lifting the spring loaded detent pins 33 and freeing the drums for angular movement. Thereafter crank 42 and shaft 43 are rotated at the control station 44. The drums 16 and 17, through the intermediary of the drum control shaft 37 and gears 38 and 40, will be shifted synchronously angularly through 180°. Thus said roll is moved to the lowermost position, as shown in Fig. 2. This angular movement preferably is counterclockwise, for example, in order to aid in maintaining proper tension upon the web 23a. As the paper roll is moved to the lower position, it engages the counterweighted brake 39 just prior to which the weighted belt 25 should be lifted off of the roll. Reliance for proper tension upon the web 23a thereafter is placed in the brake 39. The paper roll moves into its final and lower position when detents 33 drop into the next successive perforations 35 in the drums 16 and 17.

This raises one pair of coaxial arbors and makes them accessible for the installation of the next roll. Said arbors are withdrawn, as above mentioned, and are inserted into the core of the new roll, and the latter is made ready for a "running change-over."

The operator of the machine by observing or feeling the now nearly exhausted roll, can determine when to make the change-over. In order to make the oncoming web of the new roll adhere to the outgoing old web, glue is painted upon the outer surface of the web of the new roll near the leading edge thereof, and the new roll is given a slight angular velocity. The leading edge of the new web is brought down into the so-called "vortex" formed by the expiring web and the guide roll 24. The expiring web and the guide roll engage the leading edge of the new roll, pressing the glued portion thereof into the expiring web. Simultaneous with the engagement of the leading edge of the new roll, the web of the expiring roll is cut manually by a suitable cutting tool.

The above-mentioned adjustments of the lateral position of the web can be made while the rolls are paying out, that is, the frame members can be shifted axially in the same direction in carefully controlled minute increments while the machine is in operation.

Although only one embodiment of the present invention has been illustrated and described in detail, it is expressly understood that the invention is not limited thereto. For example, instead of operatively interconnecting the control elements at the control station with the shafts 37, 51 and 53 by mechanical means suitable electrical interconnections can be employed.

It will be understood by those skilled in the art that various changes and modifications may be made without departing from the spirit and scope of the invention, and it is intended, therefore, in the appended claims to cover all such changes and modifications.

15 What is claimed is:

1. In apparatus of the class described, the combination comprising a carriage member; a pair of main frames resting upon said carriage member; a pair of angularly shiftable drums mounted respectively in said main frames; a main frame spreading and closing shaft in threaded engagement with at least one of said main frames; mechanism for rotating said spreading and closing shaft; a collar member engaging a peripheral groove in said spreading and closing shaft whereby the latter is adapted for angular movement free of the former; means for restraining said collar member from angular movement; a threaded axial shift shaft in threaded engagement with a portion of said collar whereby an axial thrust is conveyable to said spreading and closing shaft in response to rotation of said axial shift shaft; means for transmitting a torque to said axial shift shaft; and mechanism for interconnecting said angularly shiftable drums for synchronous angular movement about their axes.

2. In apparatus of the class described, the combination comprising, a carriage member; a pair of frame members resting upon said carriage member; frame spreading and closing means comprising a threaded shaft which is in threaded engagement with both of said frame members, such shaft having the direction of the threads thereof which engages one frame member opposite to the direction of the threads which engage the other frame member, and mechanism for rotating said spreading and closing shaft; mechanism for axially shifting said frame members in the same direction simultaneously comprising a collar member having a portion thereof adapted to fit over one extremity of said frame spreading and closing shaft and for engaging a groove formed in said shaft, said collar member having another portion having a threaded bore coaxial with a longitudinal recess in said frame spreading and closing shaft, means for restraining said collar member from angular movement, and a threaded shaft adapted for engaging the threaded bore of said collar member and for telescopically engaging the longitudinal recess of said spreading and closing shaft, mechanism for restraining said last-mentioned shaft from axial movement, and means for rotating the latter; a pair of angularly shiftable drums mounted respectively on said frame members; a first pair of coaxial arbors mounted respectively on said drums, a second pair of coaxial arbors also mounted respectively on said drums; and mechanism for angularly shifting said drums synchronously whereby the arbors mounted thereupon are movable in synchronism and corresponding arbors upon opposite drums are held in coaxial alignment.

3. In apparatus of the class described, a carriage member; a pair of frame members; a

frame spreading and closing shaft in threaded engagement with both of said members, said shaft being threaded in opposite directions upon opposite portions lengthwise thereof which engage said frame members; a main control station; mechanism operatively connecting said spreading and closing shaft with said main control station through which the former can be rotated; a pair of arbors coaxially mounted respectively on said frame members, adapted for axial movement thereupon, said arbors protruding a relatively short distance from respective of said frame members and adapted for rotatably supporting a core member having axially extending recesses at opposite extremities thereof for receiving said arbors, whereby support for said core member can be brought closely adjacent the extremities thereof in response to adjustment of the relative positions of the frame members; and an axial shift shaft mounted for angular movement but restrained from axial movement, said axial shift shaft having threads formed thereupon; an axial shift collar having a threaded bore for engaging the threaded portion of said axial shift shaft and having another portion for engaging a groove formed adjacent one extremity of said spreading and closing shaft; mechanism for restraining said collar from angular movement; and means for operatively connecting said main control station with said axial shift shaft.

4. In apparatus of the class described, the combination comprising: a pair of frame members; a carriage member for supporting said frame members; a pair of angularly shiftable drums mounted respectively in said frame members; a pair of arbors mounted respectively in said drums and another pair of arbors also mounted respectively in said drums; a spreading and closing shaft having upon one portion of the length thereof threads in one direction for engaging one of said frame members and having upon another portion of the length thereof threads of the opposite direction for engaging the other of said frame members, whereby ro- 45

tation of said shaft can shift said frame members toward or away from one another, said shaft having a recess extending longitudinally therein and having a mouth at one extremity thereof; a collar member associated with said recessed extremity and having a portion adapted for engaging a circumferential groove in said shaft adjacent said extremity and having another portion with a threaded bore in axial alignment with said recess; means for restraining angular movement of said collar; an axial shift shaft adapted for threaded engagement with said collar bore and adapted for telescopically engaging the recess in said spreading and closing shaft; means for restraining said shift shaft from axial movement; means for rotating said last-named shaft; and mechanism for synchronously angularly shifting said drums comprising a drum control shaft, a pair of gears mounted upon and rotatable with said control shaft for association with respective of said frame members, said gears having peripheral grooves therein and being mounted for free axial movement upon said control shaft; means upon respective of said frame members for engaging respective of said peripheral grooves in said drum control gears; mechanism for operatively interconnecting said last-named gears with respective of said drums whereby angular movement of said drum control shaft will synchronously angularly shift said drums; and mechanism for rotating said drum control shaft.
